UNITED STATES PATENT OFFICE.

WILLIAM THIEDE, OF NEW BRITAIN, CONNECTICUT.

DESIGN FOR A FOB.

50,824.

Specification for Design.

Patented May 22, 1917.

Application filed January 16, 1917. Serial No. 142,774. Term of patent 3½ years.

To all whom it may concern:

Be it known that I, WILLIAM THIEDE, a citizen of the United States, residing at New Britain, in the county of Hartford and State of Connecticut, have invented a new, original, and ornamental Design for a Fob, of which the following is a specification, reference being had to the accompanying drawing, forming a part thereof.

In the accompanying drawing:—

Figure 1 is a front elevation of my improved fob.

Fig. 2 is a bottom view of the same.

I claim:

The ornamental design for a fob, as shown.

WILLIAM THIEDE.

Witnesses:

GEO. A. STARK,
LOUIS M. SCHMIDT.
